[57] CLAIM

The ornamental design for an incandescent lamp with swingable support arm, as shown and described.

DESCRIPTION

FIG. 1 is a right side elevational view of an incandescent lamp with swingable support arm embodying my new design with the arm being shown in its outwardly swung position, the left side being a mirror image;

FIG. 2 is a top plan view thereof;

FIG. 3 is a bottom plan view thereof, the arm being shown in its inwardly swung position;

FIG. 4 is a front elevational view thereof, the arm being shown in its outwardly swung position;

FIG. 5 is a top, front, right side perspective view thereof, the arm being shown in its outwardly swung position;

FIG. 6 is a rear elevational view thereof, the arm being shown in its outwardly swung position;

FIG. 7 is a right side elevational view of a second embodiment of my new design with the arm being shown in its outwardly swung position, the left side being a mirror image;

FIG. 8 is a top plan view thereof;

FIG. 9 is a bottom plan view thereof, the arm being shown in its inwardly swung position;

FIG. 10 is a front elevational view thereof, the arm being shown in its outwardly swung position;

FIG. 11 is a top, front, right side perspective view thereof, the arm being shown in its outwardly swung position; and,

FIG. 12 is a rear elevational view thereof, the arm being shown in its outwardly swung position.
